AUTOMATIC RAILWAY GATE

Filed Sept. 17, 1927

2 Sheets-Sheet 2

UNITED STATES PATENT OFFICE.

ADAM WIDUCH, OF MICHIGAN CITY, INDIANA, ASSIGNOR OF ONE-SIXTH TO WALENTY SLIWA AND ONE-SIXTH TO STANLEY HAYDUK, BOTH OF MICHIGAN CITY, INDIANA.

AUTOMATIC RAILWAY GATE.

Application filed September 17, 1927. Serial No. 220,174.

The present invention relates to automatic railway gates and has for its object the provision of a gate which is operable by means of the train.

Another object of the present invention is the provision of a railway gate of the character indicated which may be simple in construction and efficient in its operation.

Another object of the present invention is the provision of an automatic railway gate for use with railway crossings which may be operated by the approaching train approaching the crossing from either direction of the crossing.

In a number of automatic railway gates known in the art the swinging members are so constructed as to prevent the vehicle which may find itself closed in between the gates from driving either forward or backward, in which case the vehicle would be exposed to destruction by the approaching train. Therefore a further object of the present invention is the provision of an automatic railway gate which includes swinging members operable on a vertical plane provided with means to swing on a horizontal plane so as to permit the travel of a vehicle which may find itself between the swinging members and upon the track.

Another object of the present invention is the provision of means for locking the mechanism of the gate while the gate is in an inoperative position for holding the several parts of the mechanism in rigid immovable condition so as to avoid constant wear of the mechanism which otherwise would be caused by wind or other causes exerting pressure upon the gate proper.

With the above general objects in view and others that will appear as the nature of the invention is better understood, the same consists in the novel construction, combination and arrangement of parts herein-after more fully described, illustrated in the accompanying drawings and pointed out in the appended claims.

In the drawings forming a part of this application and in which like designating characters refer to corresponding parts throughout the several views,

Fig. 1 is a top plan view of the present invention showing the swinging members in closed or operative position;

Fig. 2 is a side elevational view of the gate; 55

Fig. 3 is a side cross-sectional view of the gate taken along line 3—3 of Fig. 1;

Fig. 4 is an end view of the gate, partly in section and partly in elevation, the view having been taken along line 4—4 of Fig. 1; 60

Fig. 5 is a fragmentary side view of a bar by means of which the mechanism of the gate is actuated showing its connection with the rail, the view having been taken along line 5—5 of Fig. 4; 65

Fig. 6 is a transverse cross-sectional view through said bar and rail, the view being taken on line 6—6 of Fig. 5;

Fig. 7 is an elevational side view of a wheel constituting part of the present invention showing the means for locking said wheel while the gate is in open or inoperative position; 70

Fig. 8 is a side elevational view of a swinging member; and 75

Fig. 9 is a top elevational view of the swinging member.

Referring to the drawings in detail there are shown therein conventional rails 10 positioned upon usual ties 11. Positioned below said rails and on a plane substantially with ties 11 is a box-like housing generally indicated by 12, which housing includes rectangular box frame 13 and platforms 14 positioned upon said box frame 13 and in parallel relation with the ties, as plainly seen on Figs. 1 and 3. Adjacent the outer corners, and outside of the rails, each platform 14 is provided with an opening 15 for the purposes which hereinafter will be described. 85

For the purpose of covering the resulting space between platforms 14 outer covers 16 and central cover 17 are positioned upon the inner edges of said platforms 14, and are longitudinally disposed in relation with rails 10. Said covers 16 and 17 are in the path of a road traversing the rails. 95

Positioned over both of said openings 15 are housings each of which includes a pair of upright parallel walls 18 which are in parallel relation with the rails, and a U-shaped cover 19 which covers and fits over said parallel walls 18. For affixing said latter described housing to housing 12, or more specifically to platforms 14 said walls 18 are 100

secured or rigidly affixed to platforms 14 adjacent the edges of opening 15, and the U-shaped covers 19 at their lower ends have horizontal flanges 20 which rest upon platforms 14 and by means of which said covers 19 are mounted thereupon.

Said housing, including walls 18 and U-shaped plates 19 for the purpose of simplicity are denoted on Fig. 1 by numeral 21 10 and will be referred to by that numeral in the remaining description.

Two shafts 22 which are in transverse relation with respect to the rails 10 pass through webs of said rails and are adapted 15 for rotation therewithin, as seen on Figs. 5 and 6, and by their ends pass through the lower ends of walls 18 wherein they are rotatably mounted as shown on Fig. 4. Rigidly mounted upon said shafts 22 are pulleys 23 which are positioned within the lower end 20 of housings 21 and in the openings 15.

Mounted in the upper ends of walls 18 in housings 21 are shafts 24 which are likewise adapted for rotation within said walls 25 18. Each of said shafts 24 at its portion within the housings has a smaller pulley 25 rigidly positioned upon said last named shafts. The outer ends of said shafts project outwardly of said housings 21 and have 30 rigidly mounted thereupon swinging members generally indicated by 26. Said pulleys 23 and 25, in each housing 21, are connected by belts 27 which are crossed as plainly seen on Figs. 3 and 4.

35 For the purpose of actuating or revolving shafts 22 a pair of bars 28 are provided, one for each rail and positioned alongside thereof and outwardly of the rail track. One of said bars 28 is provided for each shaft 22 as seen on Fig. 1, so that the position of said bars 28 with respect to each other and with respect of the crossing is on a diagonal line as seen on Fig. 1. Each of said bars 28 by its outer end is pivotally secured to one of 45 the ties 11, while the inner ends of said bars 21 are suitably connected to shafts 22, and the connecting means between said bars 28 and shafts 22 include links 29 which have reduced upper ends by means of which said links are pivoted within bars 28 by pins 30. The lower ends of said links 29 are bifurcated for receiving therewithin the outer end of lever 31 which is rigidly secured to each of shafts 22. Each of said bars 28 50 is adapted to be pressed upon by the wheels of the train, and the ends of said bars 28 adjacent shaft 22 have a curved or inclined upper face so as to facilitate easy engagement of the train wheels approaching from 65 the direction to which said inclined inner ends point.

The two pulleys 23 on the left side of the track are connected by means of chain, belt or cord 32 of which one end is secured to 65 one pulley 23 as at 33 and remains at a point

which is uppermost when the swinging members 26 are in an operative or closed position as plainly seen on Fig. 3. The other end of said cord 32 is secured to the opposite pulley 23 on the same side of the track and remains at the lowermost point upon said last named pulley as at 34 when the gates are closed. A similar cord 35 connects the two pulleys 33 on the other side of the track, but that one end of said cord is at the uppermost point of the pulley 23 which remains on the right side of the crossing, reference being had to Fig. 1, when the gates are closed. The other end, of said cord 35 is secured to the opposite pulley 23 on the same side of the track and the securing point is lowermost when the gates are in closed position. Said cords 33 and 35 are adapted to operate simultaneously regardless from which direction the train approaches.

Assuming that the train approaches from the direction indicated by arrow in Fig. 1, the wheels of the train will exert pressure upon bar 28 at the right side of the crossing which will bring about a downward swinging movement of lever 31 due to the downward pressure of link 29 at the outer end of said lever 31. This will cause the rotation of shaft 22 toward the approaching train which will cause the rotation of pulleys 23 on the right side of the crossing in the same direction, which in turn will impart a rotary movement of smaller pulleys 25 on the same side of the crossing in the reverse direction due to the crossed belts 27. The rotation of pulleys 25 will rotate shafts 24 in the same direction causing the downward swinging movement of gates 26 on the same side of the crossing.

Simultaneously with the above operation 105 cord 35 will be wound upon pulley 23 which remains adjacent bar 28 now under discussion, or in other words said cord 35 will be pulled toward or in the direction of said last named bar 28, which operation will 110 cause the rotation of pulley 23 to which the opposite end of cord 25 is attached, and since said end of said cord 35 is attached to the pulley 23 now in question at a point which is diametrically opposite from the pulley adjacent said bar 28, the rotation of said pulley to which said other end of said cord 35 will be rotated in the reverse direction from that to which pulley 23 adjacent bar 28 is rotated. This operation will cause the rotation of shaft 22 in the reverse direction from the direction of the first mentioned shaft 22, that is in the direction away from the train approaching from the direction indicated by arrow on Fig. 1. The rotation of said shaft 22 on the left side of the crossing will also 115 impart a rotary movement to the pulley 23 on the opposite side of the railroad track and this operation will cause the rotation of smaller pulleys 25 on said left side of the 120

track in the reverse direction from the rotation of pulleys 23 on the same side of the track, due to the crossed belts 27. This operation will cause rotation of smaller shafts 24 in the direction of rotation of said smaller pulleys 25, in consequence of which the swinging members 26 on the left side of the crossing will be brought to an operative or closed position illustrated on Figs. 1, 2 and 3.

Assuming that the gates 26 are open or in upright position and the train approaches the crossing from the opposite direction from that indicated by the arrow on Fig. 1, the train wheels will press upon bar 28 on the left side of the crossing, reference being made to Fig. 1, which will cause the rotation of shaft 22 toward the direction of the approaching train through the medium of link 29 and lever 31, as already described. This operation will cause the rotation of pulleys 23 on the left side of the crossing in the direction of the rotation of shaft 22 on the same side of the crossing and swinging members 26 on the same side of the crossing will be brought to closed or horizontal position by virtue of the rotation of pulleys 25 on the same side of the crossing, due to the operation of the crossed belts 27. Simultaneously with this operation cord 32 is wound upon the respective pulley 23, normally, when the gates are in upright position the end of said cord 32 remaining substantially on the plane with platform 14, in consequence of which operation said cord will be pulled in the direction of the approaching train from the left side of the crossing, and the other end of the crossing, which normally also remains substantially on the plane with platform 14, will cause the rotation of the opposite pulley 23 on the same side of the railroad track in the reverse direction from that of the pulley to which end 33 of cord 32 is attached. In consequence of the rotation of pulley 23 to which end 34 of cord 32 is attached, the respective shaft 22 will also rotate with said pulley and will cause the rotation of the opposite pulley 23 on the other side of the railroad track, and the two pulleys will cause the rotation of their respective smaller pulleys 25 in the reverse direction through the medium of belts 27, whereby swinging members 26 on the right side of the track will be brought to horizontal or closed position.

It is observed that when the four swinging members 26 are in an upright or open position cord 32 remains substantially on a horizontal plane running through platforms 14 and the desired operation of several pulleys 23 and their respective swinging members 26 is due to the position of the two ends of each of the cords 32 and 35 with relation to the respective pulleys with which said ends cooperate. Thus when the swinging members 26 are in an upright or open position end 33 of cord 32 will remain on its cooperating pulley 23 at a point which is nearest to the crossing and substantially on the plane with platforms 14, whereas end 34 of said cord 32 will remain on its cooperating pulley 23 at a point farthest from the crossing and also substantially on the horizontal plane with platforms 14. A similar position of cord 35 is also had in respect to its cooperating pulleys 23 on the other side of the track. There, however, the end of cord 35 which is nearer to the adjacent bar 28 remains attached to its cooperating pulley 23 at a point which is nearest to the crossing, while the opposite end of said cord 35 passes underneath the cooperating pulley 25 and remains attached to said pulley at a point which is farthest away from the crossing. The position of said cord 35 is likewise substantially on a horizontal plane with platforms 14 when the swinging members 26 are in an upright or open position.

It is observed that when the gates 26 are in an upright or open position end 33 of cord 32 and end of cord 35 which is upon its cooperating pulley adjacent its respective bar 28 remain at points on horizontal plane with platforms 14 as already mentioned, and when the rotation of said pulleys is brought about by operation of either of the bars 28 due to the pressure by train wheels, the two ends in question of cords 32 and 35 are pulled upon and shifted to the point on a vertical line with the respective housings 21, and in order that said cords 32 and 35 may be guided in said shifting movements and in order that interference of said cords may be avoided with the respective cover 16, pulleys or rollers 36 are provided for each cord 32 and 35 beneath which pulleys 36 said cords are passed. Said pulleys are positioned upon platforms 14 and adjacent the respective housings 21 near the ends of cords 32 and 35 now under discussion as plainly seen on Figs. 1 and 3. Said pulleys 36 rest upon bifurcated stands or supports 37 which are mounted upon the respective platforms 14. In order that U-shaped covers 19 of the respective housings 21 may not interfere with the movement of the respective cords 32 and 35, a longitudinal slot 38 is made in the respective U-shaped covers 19 through which said cords 32 and 35 are passed.

When the gates 26 are in a horizontal or closed position the attached ends of the two cords 32 and 35 at their respective pulleys 23 will remain in a vertical diametrical plane running through the several pulleys 23 as shown on Fig. 3.

It is further observed that all the pulleys 23 are sufficiently wide to accommodate both the belts 27 and the cords 32 and 35 and said cords may be attached to their respective pulleys at the ends of said pulleys 23 which

are either nearest to or farthest removed away from the railroad track.

At the ends of covers 16 which are adjacent to rollers 36 slots 38 are made permitting free passage of the respective ends of cords 32 and 35 as seen on Figs. 1 and 3.

It is observed that each of bars 28 is near to the crossing so that when the train is upon the crossing its wheels will exert pressure upon both of said bars. This, however, will not in any way interfere with the operation of the gates as is apparent from the hereinabove description.

Each of said swinging members 26 includes main portion 40 with opening 41 wherein shafts 24 are fitted. The outer end of said main portion 40 has weight 42 to facilitate opening of the gates when the train has passed and released the pressure upon

either of the bars 28. Hingedly affixed to the inner end of said main portion 40 by hinge 43 is arm 44 which is adapted for horizontal swinging movement upon hinge 43.

Said hinges 43 upon said swinging members 26 allow arms 44 to open only in one direction, and said hinges are upon the outer faces of said swinging members 26 as seen on Figs. 1 and 9, in consequence of which arrangements said arms 44 are permitted to

open outwardly of the railroad track. Each of said swinging members 26 is further provided with coil spring 45 which by one of its ends is affixed to the main portion 40 of each of said swinging members while the other end of said spring is affixed to the swinging arm 44, as plainly seen on Figs. 8 and 9.

Each of said springs 45 remains upon the face of each of the swinging members 26 which is opposite to the face to which hinge 43 is attached.

The construction of said swinging members 26 hereinabove described allows a vehicle which finds itself upon the railroad track at the time the train is approaching and the swinging members 26 are in horizontal or closed position, to escape notwithstanding the closed swinging members 26 by either continuing the travel or turning backwardly and the pressure exerted upon ends

44 by the vehicle will cause said ends to swing horizontally upon hinges 43 and to assume angular positions in respect of the main portions 40 of said swinging members 26. As soon as the pressure of the vehicle

upon ends 44 is removed, that is when the vehicle has passed the same, spring 45 will draw arms 44 to their normal position shown on Fig. 9.

One of pulleys 23 is provided with disk 46 upon one of its ends which has upon its periphery a projecting tooth or lug 47 which is at the lowermost point upon the periphery of said disk 46 when the swinging members 26 are in open or upright position. Said

projection 47 is adapted to fit in a depression corresponding in shape to said projection, which depression is made in block 48 which is adapted for upright shifting movement within frame 49, said frame having horizontal lugs 50 by means of which the frame is mounted upon any suitable base. Said frame 49 has grooves 51 within which the reduced ends of block 48 are adapted to fit and in which said reduced ends are adapted for upright sliding movement. Said block 48 has at its lower end bores 52 within which coil springs 53 are adapted to fit. The lower ends of said coil springs 53 rest upon the base. Said springs 53 exert pressure upon said block 48 for urging the same toward disk 46. Assuming that the swinging members 26 are in open or upright position the relative position of disk 46 and projection 47 in respect of block 48 will be the same as shown on Fig. 7. At the approach of the train pulley 23 will rotate and will bring projection 47 out of engagement from block 48.

The above arrangement permits all of the swinging members 26 when the same are in open position to remain stationary in their position and any swinging of the same by wind or any other cause is thereby prevented. Since there is an operative connection between all four pulleys 23 through cords 32 and 35 and shafts 22 and since all of said pulleys 23 are actuated no matter from which direction the train approaches the crossing, it does not matter upon which of the four pulleys 23 disk 46 with its projection 47 is positioned, and said disk 46 and projection 47 will perform their intended functions with respect to all of swinging members 26.

When the train has passed the crossing, then the weights 42 at the outer ends of said swinging members 26 will bring said swinging members to open or upright position and will recondition the mechanism to its original condition. Then disk 46 will be brought to the position illustrated on Fig. 7 so that projection 47 would engage the depression in block 48 for the purposes hereinabove described.

While there is described herein a preferred embodiment of the present invention, it is nevertheless to be understood that minor changes may be made therein, without departing from the spirit and scope of the invention as claimed.

What I claim as new is:

1. An automatic railway crossing gate comprising a platform, a pair of housings on each side of the crossing, lower pulleys positioned within said housings, shafts rigidly connecting each pair of pulleys on each side of the crossing, upper pulleys disposed in said housings, belts connecting the lower pulleys with said upper pulleys, swinging members connected to said upper pulleys, bars operatively connected with each of said

shafts and arranged lengthwise of the rails on each side of the crossing, each of said bars being adapted for actuation by the train wheels, cords connecting the opposing pulleys on each side of the track, said bars being adapted to selectively rotate the respective shafts for bringing said swinging members from upright to horizontal closed position, and means for frictionally engaging one of said pulleys when the gates are in upright open position for preventing swinging of the same.

2. An automatic railway crossing gate comprising a plurality of lower pulleys, a plurality of upper pulleys, swinging members mounted upon said upper pulleys, means for actuating said lower pulleys for closing or opening said swinging members, and means for frictionally engaging one of said lower

pulleys when said swinging members are in 20 an opened position for preventing movement thereof.

3. An automatic railway crossing gate comprising a plurality of lower pulleys, a plurality of upper pulleys, swinging members mounted upon said upper pulleys, means for actuating said lower pulleys for closing or opening said swinging members, and means for frictionally engaging one of said lower pulleys when said swinging members are in an opened position for preventing movement thereof, said means including a block positioned below said one pulley and a projection upon said pulley for engaging said block.
